UNITED STATES PATENT OFFICE.

REINHOLD BRÄUER, OF SPEYER-ON-THE-RHINE, GERMANY.

TRACTION MACHINE.

Application filed March 4, 1927, Serial No. 172,814, and in Germany March 4, 1926.

My invention relates to improvements in traction machines which are adapted for pulling or pushing loaded and unloaded vehicles. One of the objects of the improvements is to provide a traction machine which is adapted to move heavy vehicles, and which can be easily and rapidly steered. Another object of the improvements is to provide a machine which can be used for operating the gearing of turntables, cranes and the like. With these objects in view my invention consists in providing a wheeled traction machine equipped at one or both ends with members adapted to be moved in vertical direction for partly supporting the vehicle to be moved, the said members being constructed so that they are in frictional engagement with the said vehicle and are so disposed that the said frictional engagement is not interfered with when driving through curves of small radius. In addition to the mechanism for driving the traction machine means are provided for connecting the motor of the machine with the driving mechanism of other machinery such as turntables, cranes and the like.

For the purpose of explaining the invention an example embodying the same has been shown in the accompanying drawing in which the same letters of reference have been used in all the views to indicate corresponding parts. In said drawings,

Fig. 1, is an elevation showing the traction machine,

Fig. 2, is a top plan view of Fig. 1,

Fig. 3, is a partial elevation partly in section showing the manner of connecting the machine with a vehicle,

Fig. 4, is a top plan view of Fig. 3 partly in section,

Fig. 5, is diagrammatical plan view showing my improved traction machine as used in connection with the driving mechanism of a turntable,

Fig. 6, is a sectional elevation taken on the line 6—6 of Fig. 5, and

Fig. 7, is a sectional elevation taken on the line 7—7 of Fig. 5.

In the example described hereinafter reference will be made to a traction machine designed for moving railway cars. But I wish it to be understood that my invention is not limited to such use.

As shown my improved traction machine

comprises a frame composed of a plate 6, 55 side members 61, end members 10, and a cage 62 provided with a seat 46 for the engineer. The end members 10 are connected with the plate 6 by means of a pivot bolt 5 disposed longitudinally of the traction machine so 60 as to permit rocking movement of the end members 10 relatively to the plate 6 in transverse direction, springs 7 fixed to the plate 6 at opposite sides of the pivot bolt 5 supporting the plate 6 on the end members 10. 65 In vertical slots 9 provided at the ends of the side members 61 axles 2 are located on which the end members 10 are supported at their ends, and on which wheels 50 are mounted. It appears therefore that the 70 plate 6 comprising the main part of the frame is elastically supported on the wheels 50. At the bottom part of the cage 62 a motor 4 is provided, the shaft 51 of which is connected by chain and sprocket gearings 75 3 with the axles 2.

On the end members 10 supporting members 11 are provided, which are adapted to be extended in vertical direction for engaging the front or rear part of the frame of 80 a car. The said supporting members are adapted to be shifted transversely of the traction machine, for which purpose they are mounted on segmental guide ways 52, and connected by arms 53 with vertical pivot 85 bolts 12 fixed to the plate 6. If desired, anti-friction bearings may be provided for the supporting members 11 in order to reduce the friction of said members on the guide ways 52. The said supporting members may have any known or preferred construction. For example, they may be in the form of lifting jacks provided with mechanical operating means. In the example shown in the figures hydraulic jacks are provided, 90 the said hydraulic jacks comprising vertical cylinders having plungers 15 reciprocating therein, the pipes 13 for supplying pressure liquid to the said jacks being passed through the pivot bolts 12 and to a pipe 14 connected with a suitable pump. The said pump is adapted to be operated by hand or from the motor, the said operating or the controlling means being located near the engineer's seat 46. Suitable mechanical operating means 95 for the jacks 11 may consist for example of worm gearings or toothed racks and chain and sprocket gearings permitting operation 100 105 110

of the jacks from the engineer's seat. In any case the construction should be so that the transverse movement of the supporting members is not interfered with.

5 For connecting the vehicle with the traction machine suitable coupling means are provided. As appears more particularly from Figs. 3 and 4, at the height of the hook 22 of the vehicle, coupling means are secured to the cage 62, which coupling means are adapted to be adjusted in longitudinal direction according to the length of the buffers of the vehicle, so that the buffers are in engagement with the traction machine 10 when using the same for pushing the cars, while the coupling means are operative when pulling the cars. Further, the said connection prevents the traction machine from being elevated at the end remote from the vehicle by the pressure exerted on the supporting member 11 by the frame of the vehicle, which is particularly important when starting the movement of the vehicle. To the cage 62 a pair of angle irons 16 are 15 fixed which provide bearings for a cranked shaft 17 formed with a handle 23. The cranked portion of the said shaft is embraced by an eye 18 of a screw-bolt 54 screwing in a bushing 19 provided with an arm 20 25. From the opposite side a screw 20 screws in the said bushing 19, which screw is rotatably mounted in a bore of a ring 21 adapted to engage the hook 22 of the vehicle. The screws 20 and 54 are provided respectively with left and right screw threads, so that when turning the bushing 19 the length of the coupling is enlarged or reduced. For connecting the coupling to the hook 22, the cranked shaft 17 is rocked with 30 its cranked portion outwardly, in which position the ring 21 can be placed on the hook 22. Thereafter the cranked shaft 17 is turned to the right, whereupon the coupling is in reliable engagement with the hook 22. 35 The handle 23 may be provided with suitable gearing for operation from the seat 46 of the engineer. In the example shown in the figures the cranked shaft 17 is horizontal. But I wish it to be understood that I do not 40 limit myself to this feature, and that in some cases the said shaft is disposed vertically, in which case the gearing for operating the same from the seat of the driver is more simple in construction.

45 When driving through curves the hook 22 is moved laterally and away from the median axis of the vehicle, by reason of the eye 18 engaging the cranked portion of the shaft 17. Thus the coupling follows the 50 said lateral displacement.

55 The connection of the buffers 56 with the frame of the traction machine is effected through the intermediary of a leaf spring 24 rockingly mounted at 47 and adapted to 60 engage the buffers by means of blocks 25

fixed to the ends of the leaf spring. When driving through curves the buffers cause the spring 24 to rock about the fulcrum 47, so that the engagement of the buffers with the traction machine is not interfered with. 70 In some cases in lieu of the leaf spring 24 a rigid rocking beam is provided, which is adapted for engagement with the buffers. As shown the leaf springs 24 are disposed within the cage 62. In some cases I mount 75 the same outside the said cage. By being mounted on the segmental guide way 52 also, the supporting member 11 follows the lateral displacement of the front part of the frame of the vehicle driving through curves. Thus 80 dangerous braking pressures are avoided, which would cause loss of energy.

85 In a modification of the apparatus I provide two supporting members such as 11 at both sides of the frame of the traction machine, which supporting members engage the frame below the buffers. My traction machine can also be used for driving the vehicle to the work shop in case one of the 90 axes thereof is broken.

95 The end parts of the frame of the machine, which when using the same are passed below the end parts of the frame of the vehicle, are comparatively low, so that they do not interfere with certain parts of the 95 equipment of the vehicles disposed below the said end part of the frame, such for example as parts of the brake system, the heating system etc.

100 In some cases I provide my improved machine with subsidiary mechanism by means of which it may be used for various purposes, for example for driving other machinery used on the track, such for example as cranes, turntables and the like. As 105 shown in Figs. 1 and 2, at one side of the machine a gearing is provided, which is adapted to be connected with the motor shaft 51 by means of a clutch 33 through the intermediary of a chain and sprocket gearing 33' 110 and a shaft 56, the said clutch being constructed so that it is adapted to connect the motor shaft 51 either with the chain and sprocket gearing 3 for driving the traction machine, or with the chain and sprocket 115 gearing 33', so that only one of the said operations can be performed at a time. The said subsidiary gearing is mounted on a bracket 57 fixed to one of the side members 61 of the frame of the machine, and it comprises a rotary shaft 26 connected with the shaft 56 by means of a bevel gear 58, a frame 31 rockable and longitudinally shiftable on the shaft 26, a shaft 27 mounted in the frame 31, spur gears 29 and 28 120 connecting the shafts 26 and 27, and a spur gear 30 keyed to the shaft 27 and adapted to be thrown into engagement with the gearing of the machinery to be driven from the motor 4. It will be understood that the 125

shaft 26 is provided with a long groove engaged by a key fixed to the gear wheel 29, so that the said gear wheel is adapted to be rotated by the shaft 26 in any position.

5 In order to operate, for example, the driving mechanism of a turntable, the gear wheel 30 is rocked into engagement with a gear wheel of the driving mechanism of the turntable, the clutch 33 is set into position for disconnecting the driving mechanism 3 from the motor shaft and connecting thereto the chain and sprocket gearing 33', and the motor is started. After turning the turntable into the desired position the clutch 33 is 10 again set into position for disconnecting the chain and sprocket gearing 33' from the motor shaft, and connecting thereto the driving mechanism of the traction machine, whereupon the vehicle is removed from the 15 turntable.

In many cases the length of the turntable will not be sufficient to support both the vehicle and the traction machine. Therefore, I provide the turntable with an extension 20 permitting the traction machine to be placed thereon together with the vehicle. A suitable construction has been shown in Figs. 5 and 6. As appears from the said figures, an annular rail 34 is located all around the 25 turntable, and on the said rail a segmental rail 34^a provided with rollers 35 is movable, the said segmental rail providing a support for rail extensions 38^a disposed in alignment with the rails 59 of the turntable. The segmental rail is connected with the turntable by means of a plate 36 connected with the turntable by means of a universal joint 37 permitting the said plate to yield upwardly and about the longitudinal axis of the 30 turntable, so that the plate yields to any displacements of the segmental rail 34^a. At the rear of the said plate stop members 39 are provided, which are adapted to hold the plate in the proper position when turning the turntable and the rail 34^a. Preferably, 35 the segmental rail 34^a is made in sections connected with each other by a hinge 48 or the like.

At the side of the rails 59 driving mechanism for the turntable is provided, and the 40 said driving mechanism comprises a cranked frame 40 rockingly mounted on the turntable at 41, the said frame being elastically supported on a spring 60 and acted upon by a screw 65 screwing in a bail 43 and adapted to force the frame 40 downwardly. In the cranked portion of the frame 40 a roller 42 is mounted on a shaft 63 which roller is in engagement with the rail 34. To the 45 shaft 63 a bevel gearing 45 is keyed which is in mesh with a bevel gear wheel 64 keyed to a shaft 44 mounted on the frame 40 and having a spur gearing 32 keyed thereto. The said spur gearing 32 is adapted for

engagement with the aforesaid spur gear 30 65 shown in Figs. 1 and 2. By means of the screws 65 and the spring 60 the pressure on the roller 42 can be regulated at will, so that the friction between the said roller and the rail 34 is sufficient to turn the turntable. 70

When using the turntable in connection with the traction machine, the said traction machine moves the vehicle on the rails 59, and, if the length of the turntable is not 75 sufficient, one of the axles of the machine is supported on the extension 38^a. Preferably, the supporting member 15 is first lowered, in order to release the end part of the turntable and more particularly the extension 80 38^a thereof from the pressure of the vehicle, whereupon the mechanism comprising the gear wheel 30 is operated in the manner described above for turning the turntable, the driving power of the motor 4 being 85 transmitted to the roller 42.

If it is desired to operate a crane by means of the motor 4, the gear wheel 30 is thrown into engagement with a part of the driving mechanism of the said crane. Otherwise, 90 the traction machine can also be used for moving the crane on the track.

From the above description of the invention it appears that by supporting or partly 95 supporting one end of the vehicle on the supporting member or jack 11 heavy loads can be moved by means of the traction engine, and that by having the said supporting member movable transversely of the machine 100 the proper engagement between the same and the frame of the vehicle is not interfered with when driving through curves. Ordinarily the frictional engagement between the supporting member and the vehicle will be sufficient for moving the vehicle. But in 105 some cases, and more particularly in case of jars it is desirable to have a positive connection between the parts, which connection is provided by the coupling members 19, 21 and the beam or spring 24. The construction 110 of the said parts is such that in curves no lateral stresses are produced, the coupling member 19 being shiftable on the cranked shaft 17, and the beam 24 yielding forwardly and rearwardly by reason of its pivotal connection with the fulcrum 47. The mechanisms of the machine can be readily controlled by the engineer, because the operating parts of the said mechanisms, and more particularly of the engine, the coupling 115 means and the brake, are operative from points near the seat of the engineer.

While in describing the invention reference has been made to a particular example 120 embodying the same, I wish it to be understood that my invention is not limited to the construction shown in the drawings, and that various changes may be made in the 125

general arrangement of the apparatus and the construction of its parts without departing from the invention.

I claim:

- 5 1. A traction machine, comprising a wheeled frame, a transverse segmental guideway on said frame, a supporting member movable on said guideway, means for lifting said member into frictional engagement with a vehicle, and driving means for said machine.
- 10 2. A traction machine, comprising a wheeled frame, a supporting member movable on said frame, means for lifting said member into frictional engagement with a vehicle, coupling means on said machine for positively coupling said vehicle, said coupling means comprising a rod extending transversely of said wheeled frame and an eye embracing the same, and driving means for said machine.
- 15 3. A traction machine, comprising a wheeled frame, a supporting member movable on said frame, means for lifting said member into frictional engagement with a vehicle, a transverse member on said frame rockable about a vertical axis and in position for pushing engagement with a vehicle, and driving means for said machine.
- 20 4. A traction machine, comprising a wheeled frame, a supporting member movable on said frame, means for lifting said member into frictional engagement with a vehicle, and driving means for said machine remote from the end of the frame, the height of said frame at said end being less than that of the bottom parts of the equipment of a vehicle located below the end parts of the frames of the vehicles to be moved.
- 25 5. A traction machine, comprising a

wheeled frame, an engineer's seat, driving means for said frame, a supporting member movable on said frame, means for lifting said member into frictional engagement with a vehicle, means on said frame for positively coupling the vehicle and frame, said driving means, coupling means and lifting means being operative from a point near said seat, and driving means for said machine.

6. A traction machine, comprising a wheeled frame composed of three sections, two connected with the wheels and the third one yieldingly supported on said two sections and having slots permitting a play relatively to the axles of said wheels, a supporting member movable on said frame, means for lifting said member into frictional engagement with a vehicle, and driving means for said machine.

7. A traction machine, comprising a wheeled frame, a supporting member movable on said frame, means for lifting said member into frictional engagement with a vehicle, a toothed gear on said frame adapted for operative engagement with operating mechanism of an apparatus separate from the machine, driving means for said machine and gear, and means for coupling said driving means with the wheels of the frame and with said gear.

8. A traction machine, comprising a wheeled frame, a supporting member mounted on said frame for movement transversely thereof, means for lifting said member into engagement with a vehicle, and means for driving said wheeled frame.

In testimony whereof I hereunto affix my signature.

REINHOLD BRÄUER.
